UNITED STATES PATENT OFFICE.

HARRY SPENCER BENNETT, OF BETHLEHEM, PENNSYLVANIA, ASSIGNOR TO THE BAB-COCK & WILCOX COMPANY, OF BAYONNE, NEW JERSEY, A CORPORATION OF NEW JERSEY.

WASTE HEAT BOILER.

Application filed May 14, 1920. Serial No. 381,333.

This invention relates to steam boilers of the water tube type and particularly boilers for utilizing the heat of waste gases from open hearth steel furnaces or the like.

In the type of boilers to which the invention relates there is provided a series of inclined water tubes extending through a chamber across which baffles are arranged so that a series of passes are provided through which the hot gases travel in passing through the chamber, the chamber generally being provided with a flat roof which extends the entire length thereof. In such construction the boiler water tubes at the front end of the chamber lie only a short distance beneath the roof of the chamber and usually a series of superheater tubes are arranged beneath the roof of the chamber and extend above the second pass and overlie the first baffle. Comparatively little space therefore exists between the upper end of the first baffle and the roof of the chamber and this space is more or less obstructed by the superheater tubes. It has been found that this space is insufficient to permit free passage of the hot gases the result being that they are retarded in their flow by the restricted area above the baffle and by the superheater tubes arranged at this point. On account of such restriction and on account of the fact that in passing through such restricted area the gases are compelled to pass to a considerable extent longitudinally of the superheater tubes it has been found that solid matter is deposited upon the superheater tubes and other parts adjacent thereto which frequently results in clogging the space between the tubes to such an extent as to seriously interfere with the operation of the boiler. This has been found particularly true where boilers of the type heretofore described are employed in utilizing waste gases from steel furnaces.

The present invention aims to overcome this difficulty and it has been found that if the roof of the chamber and particularly that portion of the same lying above the first pass and part of the second pass be elevated as hereinafter pointed out the difficulties mentioned will be overcome. By such modification the space allowed for the passage of gases above the first baffle is materially increased so that the flow of gases

will not be retarded and deposition of solid material on the superheater tubes or other parts is obviated, this result probably being due in part to the fact that by means of such elevation of the roof of the chamber the hot gases in travelling from the first pass into the second pass of the boiler move to some extent transversely of the superheater tubes and do not travel longitudinally of such tubes to the same extent as in the prior constructions heretofore mentioned.

The present invention therefore results in producing a boiler which has marked advantages in operation and considerable increase in efficiency over prior constructions in which the parts have not been modified in the manner stated.

The drawing accompanying this specification and forming a part thereof shows in longitudinal section a boiler of the type heretofore referred to having the present invention embodied therein.

Referring to the drawing in detail 10 represents the front wall and 11 the rear wall of the boiler chamber it being understood that suitable side walls are also provided. Arranged in the chamber is a bank of water tubes 12 secured in headers 13 and 14 arranged respectively at the front and rear of the chamber. The header 13 is arranged at a higher elevation than the header 14 with the result that the water tubes 12 are inclined from the front toward the rear of the chamber. The headers 13 and 14 are connected by horizontal circulating tubes 15 and vertical tubes 16 to a steam and water drum 17 arranged at the top of the chamber. Superheater tubes 18 are mounted in the upper portion of the chamber and are secured in headers 19 and 20, one of which may be suitably connected to the steam space of the drum 17 and the other to a steam main (not shown) leading from the boiler. Arranged transversely of the chamber and spaced from the front wall thereof is a bridge wall 21 and above the same there is arranged a baffle 22 which extends from one side to the other of the chamber transversely of the water tubes and upwardly to approximately the height of the water tubes. The wall 21 and baffle 22 may be generally designated as a front baffle. At the rear of the front baffle and spaced therefrom there

is provided a wall 30 extending from the roof of the chamber downwardly, beneath which there is arranged a baffle, 23, which extends from the wall 30 downwardly to approximately the bottom of the bank of water tubes. The wall 30 and baffle 23 may be designated as a rear baffle. As a result of the foregoing construction the chamber of the boiler is divided into three passes through which the gases are forced to travel in passing through the boiler. When employed for utilizing waste gases from furnaces such gases are admitted to the chamber through a pipe 24, the inlet of which is arranged in the first pass of the boiler chamber. An exit opening 25 for the spent gases is provided in any suitable place in the walls of the chamber preferably in the third pass above the water tubes. If desired the boiler may be arranged for utilizing solid fuel by providing a grate in front of the bridge wall 21.

The roof of the chamber, to the arrangement of which the present invention particularly relates, preferably consists of a portion 26 which is supported in the usual way, as illustrated, on the circulating tubes, and a portion 27 the latter of which is elevated a substantial distance with reference to the former. The portion of the roof of the chamber which is elevated extends from the front of the boiler rearwardly to substantially the center thereof so that such elevated portion overlies the major portion of the first and second passes of the boiler. The front baffle 22 is positioned beneath the elevated portion of the roof and approximately at the center thereof and the superheater tubes for most of their length lie beneath such elevated portion of the roof. The elevation of the part 27 of the roof is such that the cross sectional area of the space between the upper end of the front baffle 22 and the elevated portion of the roof is considerably greater than that of prior constructions of this character, this area being approximately the same or only slightly less than the cross sectional area of the various passes of the boiler. The effective area above the front baffle is also preferably not less than the area under the second or rear baffle.

While the roof of the chamber is preferably arranged at two different elevations as shown, since elevation of the rear portion of the roof is unnecessary from the standpoint of the present invention, it is, of course, evident that the entire roof of the chamber may, if desired, be arranged at an elevation corresponding to that of the portion 27 of the construction illustrated.

As a result of the foregoing construction the gases entering the first pass of the boiler can travel over the baffle 22 and through the superheater tubes 18 without being materially restricted in their flow, and as a result the deposition of solid material on the super-

heater tubes and adjacent parts and the clogging of the spaces between such tubes, is avoided, the construction as a whole therefore possessing substantial advantages over prior constructions of this character in that difficulties of operation are obviated and a marked increase in efficiency is secured. By providing an elevated portion of the roof above the baffle between the first and second passes of the boiler, the gases are caused to pass upwardly from the first pass over the horizontal circulating tubes into the space between the circulating tubes and the roof, and then downwardly again over the circulating tubes to the down pass. By passing the gases over the circulating tubes as described, the capacity and efficiency of the boiler is correspondingly increased.

By forming the superheater of U tubes located beneath the horizontal circulating tubes, and by extending the superheater tubes horizontally across the down pass but only partially across the up pass, as illustrated, the gases from the up pass flow upwardly past the superheater into the chamber formed by the elevated roof portion, and then, after flowing downwardly over the horizontal circulating tubes as described above, the gases pass across the tubes of the superheater. A downward flow of dust-laden gases across horizontally extending tubes results in a lesser deposit of dust than an upward flow or a longitudinal flow. The arrangement therefore avoids, or partly avoids, the deposition of dust from the gases and correspondingly increases the efficiency of the superheater.

Moreover, where a considerable number of boilers are employed for utilizing waste gases from steel furnaces, a marked increase in plant efficiency results, since with my improved construction, shutting down of the boilers for purpose of cleaning is largely avoided and a much larger number of boilers can therefore be kept constantly in use, thus avoiding loss of waste gases which takes place when boilers are thrown out of operation. With the improved construction practically all of the waste gases from the furnaces can therefore be utilized and in addition it has been found that the smelting period which formerly required a period of twenty-six hours when the old form of boilers was used, has been reduced to twenty-four hours.

Having thus described my invention what I claim as new and desire to secure by Letters Patent is:

1. In a steam boiler, an upper steam and water drum, horizontally inclined water tubes and connections between the same and said steam and water drum and comprising horizontal water and steam circulators, a baffle extending across the tubes, a roof located above said circulators, the portion of

the roof above said baffle being elevated substantially above the circulators and providing a free unobstructed space between the circulators and the roof, and a superheater 5 entirely located beneath said circulators, but not extending across the space above the first pass, whereby the gases from the first pass sweep upwardly over the circulating tubes into said space and thence downwardly over 10 said circulating tubes and over the superheater tubes to the second pass.

2. In a steam boiler, an upper steam and water drum, horizontally inclined water tubes and connections between the same and 15 said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, and a superheater 20 located beneath said circulators, the headers of the superheater being located beneath the non-elevated part of the roof and the tubes at least in part being located beneath the elevated portion of the roof but not extending across the space above the first pass whereby the gases from the first pass sweep upwardly 25 over the circulating tubes into said space and thence downwardly over said circulating tubes and the superheater tubes to the second pass.

3. In a steam boiler, an upper steam and water drum, horizontally inclined water tubes and connections between the same and 15 said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, and a superheater 20 comprising U tubes located beneath said circulators and extending over the second pass and only partially over the first pass and with the bent ends of the tubes located approximately above said baffle, whereby the gases from the first pass sweep upwardly over the circulating tubes into said space and thence downwardly over said circulating tubes and the superheater tubes to the second pass.

4. In a steam boiler, an upper steam and water drum, horizontally inclined water tubes and connections between the same and 15 said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, and a superheater 20 comprising U tubes extending parallel to said circulators above the second pass and with the bent ends of the superheater tubes

located approximately above said baffle, whereby the gases from the first pass sweep upwardly over the circulating tubes into said space and thence downwardly over said circulating tubes and the superheater tubes 70 to the second pass.

5. In a steam boiler, an upper steam and water drum, horizontally inclined water tubes and connections between the same and 75 said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, and a superheater 80 located beneath said circulators, the headers of the superheater being located beneath the non-elevated part of the roof and the tubes at least in part being located beneath the elevated portion of the roof but not extending across the space above the first pass whereby the gases from the first pass sweep upwardly 85 over the circulating tubes into said space and thence downwardly over said circulating tubes and the superheater tubes to the second pass.

6. In a steam boiler, an upper steam and water drum, horizontally inclined water tubes and connections between the same and 90 said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, and means for delivering waste-heat gases to said boiler, 95 whereby the gases from the first pass sweep upwardly over the circulating tubes into said space and thence downwardly over said circulating tubes to the second pass, the gases being made to flow across all of the circulating tubes of the boiler before entering 100 the second pass.

7. In a waste-heat steam boiler, an upper steam and water drum, horizontally inclined water tubes and connections between 105 the same and said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, and means for delivering waste-heat gases to said boiler, whereby the waste gases from 110 the first pass sweep upwardly over the circulating tubes into said space and thence downwardly over said circulating tubes to the second pass.

8. In a waste-heat steam boiler, an upper 115

steam and water drum, horizontally inclined water tubes and connections between the same and said steam and water drum and comprising horizontal water and steam circulators, a baffle extending across the tubes, a roof located above said circulators, the portion of the roof above said baffle being elevated substantially above the circulators and providing a free unobstructed space between the circulators and the roof, means for delivering waste-heat gases to the boiler,

and a superheater located beneath said circulators and extending over the second pass and only partially over the first pass, whereby the gases from the first pass sweep upwardly over the circulating tubes into said space and thence downwardly over said circulating tubes and the superheater tubes to the second pass. 15

In testimony whereof I affix my signature.

HARRY SPENCER BENNETT.
